UNITED STATES PATENT OFFICE.

ALEXANDER NOWAK, OF DOUGLAS, ARIZONA, ASSIGNOR OF ONE-HALF TO J. G. PIMPELL, OF DOUGLAS, ARIZONA.

REFRIGERATOR.

1,396,457.

Specification of Letters Patent. Patented Nov. 8, 1921.

Application filed July 28, 1920. Serial No. 399,571.

To all whom it may concern:

Be it known that I, ALEXANDER NOWAK, a citizen of the United States, residing at Douglas, in the county of Cochise and State 5 of Arizona, have invented certain new and useful Improvements in Refrigerators, of which the following is a specification.

This invention relates to receptacles for storing food and has for its object the pro- 10 vision of means whereby food may be kept fresh without the use of ice, the device being intended particularly for use in hot dry climates where ice is difficult to obtain.

The invention is illustrated in the accom- 15 panying drawings and will be hereinafter fully described, the novel features being subsequently particularly pointed out in the appended claims.

In the drawings—

20 Figure 1 is a perspective view of a refrigerator or food storage receptacle embodying my invention, the top being omitted;

Fig. 2 is a longitudinal section on the line 2—2 of Fig. 1.

25 Fig. 3 is a transverse section on the line 3—3 of Fig. 1.

The apparatus of my invention may be constructed of any suitable material and will preferably be formed of concrete. In carry- 30

ing out the invention, I form a bottom 1 which will be a single slab of concrete pro- 35

vided on its under side with feet 2 whereby it may be supported out of contact with the floor of the room in which it is to be located.

35 This slab is provided at its edges on its upper side with lugs or enlargements 3 which have their upper surfaces in the same horizontal plane and constitute supports for the side walls, openings 4 being formed verti- 40

cally therethrough for the reception of se- 45

curing bolts or rods. The slab may be cast in any convenient type of mold and upon its upper face at one side edge is provided with a ledge 5 forming a sill to coöperate with

45 a door 6. The upper surface of the bottom slab 1 is dished, as shown at 7, so that water will drain toward the center thereof and escape through an outlet opening 8 in which may be fitted the end of a discharge pipe 9

50 to carry the water to any point of discharge.

Preferably, as shown in Fig. 2, this pipe or hose will be bent so as to provide a goose neck trap and thereby form a water seal for the outlet to prevent obnoxious odors

from the outside air flowing back to the food 55 compartment. The end walls 10 and the back wall 11 are similar in construction although differing in dimensions, the back wall being wider than the end walls, as shown and as will be readily understood. 60 These walls will be formed of concrete slabs and will be constructed with interengaging tongues and grooves, as shown at 12, whereby the fitting of the parts together will be facilitated and fastening bolts or rods, indicated at 13, are inserted through the several walls to firmly secure them together. The thickness of the walls is greater than the thickness of the ledge 14 on the upper side 65 of the bottom slab and vertical openings 15 70 are formed in the walls, as shown, the lower ends of the openings being at the inner sides of the ledges 14, as shown clearly in Figs. 2 and 3. Water trickling down through the passages 15 will be thereby directed over the 75 bottom slab 1 to the outlet 8 therein. The front wall 16 is without vertical passages therethrough, the upper portion thereof being solid, while the lower portion is open to accommodate the door 6 and in the edges 80 of the door opening I secure a packing strip 17 which will coat with the edges of the door to form an air-tight joint and thereby seal the food compartment so that the outside air will not have direct access thereto. 85

Upon the inner side of the front wall 16, I provide a shoulder or rib 18 which supports one side of the ice tray 19, the said tray being provided on its other side edges with lips 20 which are fitted in openings 21 in the 90 walls of the receptacle so that the water from melting ice or from a water container placed on the tray will be directed into the passages 15 and permitted to drip down through said passages onto the bottom slab 95

1. The rib 18 is provided with an opening 22 therethrough so that the foul air from the food receptacle may rise to the top 23 of the refrigerator and escape through a vent 24 therein. The top 23 is also a concrete slab 100 cast in a proper mold and provided at its edges with depending flanges 25 adapted to fit around the outer surfaces of the walls 10, 11 and 16 and thereby hold the top in proper position. To prevent an accumulation of 105 dampness within the passages 15 and to provide for a circulation of air therethrough vent openings 26 are formed in the walls 10

and 11 near the upper ends thereof to communicate with the said passages.

When a supply of ice is obtainable, the ice is placed upon the tray 19 and the top

6 of the refrigerator fastened down. It will be noted that the tray 19 dips from its center toward its side edges so that the water from the melting ice will be directed in all directions to the passages 15 and will trickle down

10 through said passages onto the bottom 1 and eventually escape through the outlet 8. At its front edge, the tray 19 is provided with an upstanding lip 27 so that the water cannot pass through the opening 22. When a

15 supply of ice is not obtainable, a water container 28 filled with water is placed upon the tray 19, as indicated in Fig. 1, and this con-

tainer may be of any preferred form, but is preferably provided with a minute opening

20 in its bottom through which the water may very slowly escape and it may be also provided with minute escape openings, indicated at 29, in its side wall to saturate a covering 30 of felt or similar material wrapped

25 around the receptacle, as shown in Fig. 1. The water will escape very slowly through the absorbent covering and will drip through the passages 15 to the bottom slab 1 of the receptacle and inasmuch as the pas-

30 sages 15 are not dead-air spaces evaporation will occur with an attendant escape of heat from the receptacle. Perishable articles of food may thus be kept in good condition for a considerable period of time without the

35 use of ice and at a very low cost. The concrete slabs will be suitably reinforced and this material is desirable inasmuch as it is heat-resisting but other material may, of course, be employed or, if it be desired to

40 give any particular finish to the device, a

wooden or metal covering may be secured over the concrete body.

Having thus described the invention, what is claimed as new is:

1. An apparatus for the purpose set forth 45 comprising a bottom having an outlet therethrough, walls erected on said bottom and provided with open-ended passages extending vertically therethrough, one of said walls having a shoulder upon its inner side near its 50 upper end and the remaining walls having openings in the plane of said shoulder communicating with the passages through the walls, and a tray resting at one side upon the said shoulder and provided at its other sides 55 with lips engaging in the openings through the walls.

2. An apparatus for the purpose set forth, comprising a bottom having a dished upper surface and provided with an outlet at the 60 lowest point of said surface, walls erected on said bottom and provided with open-ended vertical passages therethrough having their lower ends arranged to discharge onto the dished surface of the bottom, one of the 65 walls having a shoulder on its inner side provided with a vertical opening therethrough and the remaining walls having openings in the plane of said shoulder communicating with the vertical passages 70 through the walls, and a tray having its upper surface inclined downwardly from its center toward its edges and having one edge resting on the said shoulder and provided with an upturned lip and having its other 75 edges provided with downturned lips engaging in the openings through the walls.

In testimony whereof I affix my signature.

ALEXANDER NOWAK. [L. S.]
